Specification of Letters Patent. Patented Nov. 14, 1916.

Application filed September 11, 1912. Serial No. 719,781.

To all whom it may concern:

Be it known that I, JOSEPH D. MACDONALD, a citizen of the United States, residing at Seattle, in the county of King and State 5 of Washington, have invented certain new and useful Improvements in Drills, of which the following is a specification.

The present invention pertains to improvements in drills, and more particularly 10 to that class adapted for use in mining, stone drilling, and the like.

The drill is shown in the annexed drawings, wherein:

Figure 1 is a longitudinal sectional view 15 of the drill and a portion of the engine or hammer casing to which it is attached; Fig. 2, a bottom plan view; Fig. 3, a perspective view as seen from the under side, three of the four bits being omitted; Fig. 4, a 20 vertical sectional view taken at right angles to that shown in Fig. 1, and more clearly showing the air discharge ports; Fig. 5, a like view taken on the line 5—5 of Fig. 6; Fig. 6, a cross sectional view taken on the 25 line 6—6 of Fig. 5 looking down; Fig. 7, a perspective view of one of the bits; Fig. 8, a like view of the bit-locking plug or member; and Fig. 9, a detail sectional view showing a modification of the invention.

30 The main object of the present invention is to produce a drill in which the bits may be readily positioned and secured, and as readily released and replaced when necessary or desirable. Furthermore, the construction is such that the bits will be firmly 35 held in place, and will not become loosened under the jar or impact of the hammer.

In the drawings, 1 denotes a portion of the engine or hammer casing, in the end of 40 which is seated the reduced or anvil end 2 of the drill head or chuck 3, said head being secured in place in the member 1 by the usual cross pin or member 4. The head 3 is provided with a centrally-disposed recess 5, 45 which extends upwardly into the reduced portion 2, the outer or lower portion of the recess being threaded. Ports or passages 6 extend from the upper end of the anvil portion 2 downwardly therethrough, terminating in angularly disposed passages or ports 7, which latter extend through the head 3, opening at their inner ends in the upper portion of recess or chamber 5, while their lower ends open outwardly through the side walls 50

of the head 3, and preferably at a point between the bits or bit-seats. The outer end of the head 3 is also provided with a series of bit-seats, designated by 8, the seats having the form of undercut or dovetailed grooves or slots, said grooves being radially disposed and equally spaced about the central chamber or recess 5. The formation of the grooves produces a series of intermediate sections 10, the inner wall 11 of each section being formed upon a radius somewhat greater than that of the central recess or chamber 5.

In the bottom of each bit-seat 8 there is formed a groove 12, the groove being closed at its outer end and open at its inner end; 70 that is to say, the groove opens into the chamber or recess 5, but stops short of passing through the outer wall of the head 3, forming as it were an abutment 13 for the pin 14 of the bit 15 when the latter is fully 75 positioned. The bit, as will be seen, is triangular in cross section, and is of such size at its base as to make a relatively close fit with its seat when positioned, the pin 14 passing into groove 12 and coming into contact with the abutment 13 which precludes further outward radial movement of the bit. The ends 16 of the bit will preferably 80 be inclined or given a spread, so as to produce a relatively long cutting edge 17, and 85 likewise produce points 18 which latter facilitate the cutting action of the tool.

To secure the bits in place after they are positioned, I provide a plug 19, said plug preferably having an opening 20 extending 90 centrally therethrough, and likewise provided with an external threaded section adapted to engage the threaded portion of recess 5. The outer portion or end of the plug 19 is tapered as at 21, and this tapered 95 face bears against the adjacent inclined faces 16 of the bits when the plug is screwed outwardly, thereby forcing the pins 14 into close contact with abutment 13 and consequently locking all the bits in place; see 100 Fig. 4.

By merely screwing the plug 19 inwardly to the position shown in Fig. 1 the bits may be removed, one at a time, by moving the same inwardly, there being sufficient clearance to permit such removal of the bits by reason of the walls 11 being produced upon a relatively large radius as above noted.

In Fig. 9 a slight modification is illustrated. Under such construction the groove in the bottom of the bit-seat is omitted, and a stop-pin 22 mounted in the head extends 5 above said bottom. The bit 15^a has formed in its base two aligned grooves 23 and 24, separated at their adjacent ends by an abutment 25 adapted to co-act with the pin, as will be seen upon an inspection of the figure in question. This construction likewise permits the bit to be removed and turned end for end, so that when one point becomes dull the other point may be brought into action, it being understood that the outer points, or 15 those which cut the wall of the opening being formed, receive the greatest wear.

In the operation of the drill the air which is employed to actuate the hammer is discharged into the casing or shell 1, passes 20 downwardly through ports 6 into ports 7, and thence outwardly into the hole being drilled, through the outer open ends of said ports. The air will also pass in part from ports or channels 7 into chamber 5, and out 25 through opening 20 in the bit-securing plug 19. Such air acts to blow the cuttings and dust from the hole, and to keep the same clear for direct action of the bits.

Having thus described my invention, what I claim is:—

A drill comprising a head having formed in its outer end a series of dovetail grooves forming seats, said head likewise having a centrally-disposed threaded opening; a bit for each seat, said bits being triangular in cross section and having their ends inclined outwardly toward the cutting edge of the bit; a pin carried by each bit upon its outer face, said pin, when the bit is seated, entering a groove formed in the base of the bit-seat, and adapted when the bit is moved outwardly to its full extent to contact with the end wall of the groove; and a threaded locking plug mounted in the central opening aforesaid, the outer end of the plug being 45 tapered, and when screwed outwardly, making a close fit with the adjacent inclined ends of the bits and locking them in place.

In testimony whereof I have signed my name to this specification in the presence of 50 two subscribing witnesses.

JOSEPH D. MACDONALD.
